UNITED STATES PATENT OFFICE.

ALBERT C. WYNNE, OF BIRMINGHAM, ENGLAND.

ELECTRICAL SWITCH.

1,262,424.

Specification of Letters Patent.

Patented Apr. 9, 1918.

Application filed April 17, 1916. Serial No. 91,708.

To all whom it may concern:

Be it known that I, ALBERT COURTNEY WYNNE, a subject of the King of Great Britain, residing at "Mayfield," Wychall 5 Lane, Kings Norton, Birmingham, England, have invented certain new and useful Improvements in Electrical Switches, of which the following is a specification.

This invention has reference to electrical switches of the type in which the oscillating contact-arm of the make-and-break mechanism is operated by a sliding member which, when moved in one direction, brings about the closing of the switch, 15 while its movement in the other direction causes the said switch to open.

The said invention consists in improved operating mechanism for plug and like switches, comprising a sliding and detachable pin or plunger member and an angularly-displaceable sleeve or tubular member which is mechanically connected with the contact arm; one of the said members being formed with a helical slot, groove or recess 25 which is open at one end, while the other end has a stud or lateral projection which, on the insertion of the detachable pin or plunger into the sleeve, engages and co-operates with the helical slot or groove and imparts 30 movement to the said sleeve for closing the switch; while on withdrawal of the said pin or plunger, the co-operation of the stud and slot or groove positively brings about the opening of the said switch, in the manner 35 hereinafter described.

I will first describe my invention as applied to a key-operated oscillating-arm switch embodying a quick-make and quick-break mechanism of the kind described in 40 the specification of my application for British Letters Patent dated the 9th day of March 1915 and numbered 3733; reference being made to the accompanying drawings, in which—

45 Figure 1 represents a transverse vertical section of the improved switch, showing the detachable operating key applied or connected, and the oscillating switch-arm in its "on" or "closed" position.

50 Fig. 2 is a plan of Fig. 1, but with the detachable key omitted for the sake of clearness.

Fig. 3 is a separate elevation of the detachable key and of the sliding pin or plunger element of the improved operating mechanism. 55

Fig. 4 is a detail view, partly in elevation and partly in section, of the element of the improved operating mechanism which is permanently embodied in the switch and is in 60 operative connection with the quick-make and quick-break movement.

Fig. 5 is an elevation of a slightly modified form of key, and

Figs. 6 and 7 show respectively an elevation and plan of the element which is embodied in the switch; and of its support or bearing plate. 65

Figs. 8 and 9 illustrate the application of the invention to a plug-switch. 70

The same letters of reference indicate corresponding parts in the several figures of the drawing.

In the switch shown in Figs. 1 and 2, the actual quick-make and quick-break mechanism is constructed in accordance with the invention described in the specification of my above mentioned British application No. 3733 of 1915, and the spring-tensioning cam *a* of the said mechanism is connected with 80 the oscillating contact-arm *c*, and with the central sleeve *b*, in the manner described in the said specification. 75

According to the present invention, the said sleeve *b* is adapted to constitute one 85 element of the special means or mechanism whereby the switch may be actuated from an external detachable handle *d* that carries or is associated with the second element of the said actuating arrangement, viz., a 90 sliding key-pin or plunger *e* which, on being inserted into the sleeve element by means of the said handle, brings about the closing of the switch mechanism, while its withdrawal brings about the opening of the said 95 switch.

The sleeve *b* is rotatably mounted in the center of the switch between a bed or base plate *f* and a transverse bridge plate *g*; the open upper end of said sleeve extending 100 above the top of the said plate *g*, as shown in Fig. 1, and registering with a hole or aperture in the center of the cover, while its wall is formed with a slot *b*¹ which prefer-

ably takes the form shown in Figs. 1 and 4, and embodies a long slow-pitched helical portion b^2 , a short quick pitched helical portion b^3 , and a straight lower end b^4 .

- 5 The pin or plunger e depends from the underside of, and is rigidly connected to, the handle d , and is of such dimensions that when pushed fully home into the sleeve b , it extends nearly to the bottom of the latter, 10 while its lower extremity is provided with a radially-projecting stud e^1 that is adapted to engage with and travel along the slot b^1 of the sleeve b when the plunger is inserted into or withdrawn from the said sleeve. During the insertion of the plunger, which is held against rotation by the operator's fingers, the stud e^1 travels down the helical portion b^2 of the slot b^1 and compels the angularly-displaceable sleeve to turn in 15 the clock-wise direction for stressing the quick-make and break spring whereby (after the stud has traveled past the part b^3 of the slot b^1) the oscillating contact-arm is closed or taken into engagement with its 20 fixed contacts independently of the manually operated handle or key, whereas during the withdrawal of the plunger, the sliding stud e^1 and the slot b^1 coöperate or function to turn the sleeve counter-clockwise to again 25 stress the spring and bring about the quick-break movement of the switch-arm; the disengagement of the said arm from its fixed contacts being completed before the plunger actually leaves the sleeve.
- 30 35 To prevent the slotted upper end of the sleeve that extends above the bridge-plate from spreading or expanding, the same may be fitted with an external reinforcing collar or ferrule b^5 .
- 40 The slot b^1 might be made a regular slow-pitch spiral from end to end, but when the present invention is applied to a quick make and break switch such as shown in Figs. 1 and 2, it is preferable for several reasons to 45 adopt the compound formation above referred to. For instance, the straight lower part b^4 admits of the plunger-stud working up or down therein without transmitting any movement to the sleeve, and thus the said plunger can always be pushed fully 50 home after the switch has actually closed without straining any parts of the mechanism. The step or short quick-pitched portion b^3 is used to rapidly take up the play between the sleeve element of the operating mechanism and the spring-stressing cam, either at the completion of the downward 55 operative movement of the plunger or at the commencement of its withdrawal, while the 60 long slow-pitched portion of the slot provides for a smooth and easy action during the time that the quick-make and break spring is being stressed from the positively-actuated sleeve for either opening or closing 65 the switch.

In order to positively prevent rotary or twisting movement of the plunger during its insertion into or withdrawal from the sleeve, the handle or key may be provided (as shown in Fig. 5) with a pin i which is 70 of equal length to, and is located parallel with, the plunger, and is adapted to pass through a suitable hole or aperture in the switch-cover and to engage and work within a guide hole i^1 in the bridge-plate of the 75 switch (see Figs. 6 and 7). Or alternatively, the plunger may be formed with a vertical groove or recess that is engaged by a tongue or feather piece, which can be formed out of, or attached to, the bridge-plate and is 80 so disposed that its extremity will engage the open lower end of the plunger-groove before the extremity of the plunger enters the sleeve. Or any other key or feathering 85 arrangement may be adopted which constrains the detachable plunger to make a straight sliding movement within the slotted sleeve and so obviates the necessity of the operator having to hold the key against rotation while inserting or withdrawing the 90 same.

In applying the invention to a plug switch (as shown in elevation in Fig. 8 and in plan in Fig. 9) the sliding plunger n , n^1 is carried by, or attached to the underside of, 95 the detachable plug-carrying member p , while the slotted sleeve (marked f , m in Figs. 8 and 9) is embodied in, or operatively connected with, the switch mechanism; the plug-pins q^3 , q^4 that engage with 100 the sockets q^1 , q^2 of the switch then serving as means which prevent rotary twisting movement of the plunger during its insertion or removal. As in the case of the plunger-operated switch shown in Figs. 1 and 2, 105 the plunger n , n^1 and slotted sleeve f , m , co-operate to bring about the closing of the switch during the insertion of the plunger and plug-pins into the sleeve and sockets respectively while the withdrawal of the 110 plunger with the detachable plug and its pins brings about the opening of the switch. The switch-opening movement is timed to occur before the plug-pins actually leave their sockets in order to insure that these 115 metal parts shall be electrically dead at the moment of their separation and that burning of the pins due to sparking shall be rendered impossible, so that with this arrangement, the electrical circuit is neither 120 made nor broken by the plug pins.

In the said Figs. 8 and 9, the base of the switch is marked a , while c indicates the oscillating contact arm of the switch movement. 125

Instead of providing for the transmission of angular movement to the sleeve from a sliding or straight-motion plunger through the medium of a stud or radial projection on the latter engaging a helical slot cut through 130

the walls of the former, the said sleeve may be formed with an internal helical groove for the plunger stud to work within; or a helical groove or recess of suitable length and conformation may be formed in the plunger; the co-acting stud, in this case, being fitted inside the upper end of the sleeve.

Mechanism such as above described may 10 be applied to or embodied in any kind of switch mechanism where the contact arm is adapted or designed to make an oscillating movement into and out of engagement with its fixed contacts, and is capable of being operated in its "make" and "break" directions directly or indirectly from an angularly-displaceable sleeve or equivalent member.

Having described my invention, what I claim and desire to secure by Letters Patent is:—

1. In a switch, the combination, with an oscillatory contact arm, contact means co-operating therewith and a case inclosing the same; of an angularly-displaceable sleeve 25 within said case connected with said arm to control its movements, an operating device detachable from said case and a pin or plunger carried by said device and adapted to be inserted in and withdrawn wholly 30 from said sleeve; said sleeve and plunger constituting a pair of companion members, one of which is formed with a helical slot, groove or recess, and the other with a lateral projection adapted to travel therein, whereby at each 35 insertion of said plunger in said sleeve the latter will be rotated thereby solely in a direction to cause the switch-closing movement of said arm, while its withdrawal will rotate said sleeve solely in the opposite 40 direction so as to cause the switch-opening movement of said arm.

2. In a switch, the combination, with a movable contact arm, and contact means co-operative therewith; of means for operating 45 said contact arm, comprising an angularly-displaceable sleeve connected with said arm to control its movements, and a detachable pin or plunger adapted to be inserted in and withdrawn from said sleeve; said sleeve being formed with a slot having a long, slow-pitched, helical upper portion, a short, quick-pitched helical intermediate portion and a straight lower portion, and said plunger having a lateral projection adapted to 55 travel therein, whereby the insertion of said plunger in said sleeve will rotate the latter in a direction to cause the switch-closing movement of said arm, while its withdrawal will rotate said sleeve in the opposite direction so as to cause the switch-opening movement of said arm.

3. In a switch having a case, and spaced 60 bed and bridge plates arranged therewithin, the combination, with an oscillatory contact arm, and contact means co-operative there-

with also arranged within said case; of an angularly-displaceable sleeve mounted within said case between said plates and connected with said arm to control its movements, said sleeve having its upper end extended above said bridge plate and provided with an external reinforcing collar, an operating device detachable from said case; and a pin or plunger adapted to be inserted in and withdrawn wholly from said sleeve; 75 said sleeve and plunger constituting a pair of companion members, one of which is formed with a helical slot, groove or recess, and the other with a lateral projection adapted to travel therein, whereby at each 80 insertion of said plunger in said sleeve the latter will be rotated thereby solely in a direction to cause the switch-closing movement of said arm, while its withdrawal will rotate said sleeve solely in the opposite 85 direction so as to cause the switch-opening movement of said arm.

4. In a switch, the combination, with a movable contact arm, contact means co-operative therewith and a case inclosing the same; of an angularly-displaceable sleeve within said case connected with said arm to control its movements; a handle detachable from said case; a detachable pin or plunger carried by said handle and adapted to be inserted in and withdrawn wholly from said sleeve; said sleeve and plunger constituting a pair of companion members, one of which is formed with a helical slot, groove or recess, and the other with a lateral projection 95 adapted to travel therein, whereby at each insertion of said plunger in said sleeve the latter will be rotated thereby solely in a direction to cause the switch-closing movement of said arm, while its withdrawal will 100 rotate said sleeve solely in the opposite direction so as to cause the switch-opening movement of said arm; and means for positively preventing rotary or twisting movement of the plunger during such insertion 105 and withdrawal.

5. In a plug switch having sockets for the plug pins, the combination, with a detachable plug member, and a plurality of pins or plungers carried thereby for insertion in 115 and removal from said sockets; of a movable contact arm; and means for operating said contact arm, comprising an angularly-displaceable sleeve connected with said arm to control its movements; said sleeve and one 120 of said pins or plungers constituting a pair of companion members, one of which is formed with a helical slot, groove or recess, and the other with a lateral projection 125 adapted to travel therein, whereby the insertion of said plunger in said sleeve will rotate the latter in a direction to cause the switch-closing movement of said arm, while its withdrawal will rotate said sleeve in the opposite direction so as to cause the switch- 130

opening movement of said arm; the remaining pins or plungers acting to positively prevent rotary or twisting movement of the aforesaid pin or plunger during such insertion and removal.

In testimony whereof I have hereunto set

my hand in presence of two subscribing witnesses.

A. C. WYNNE.
